UNITED STATES PATENT OFFICE

145,855

DESIGN FOR A PHOTOGRAPHIC ENLARGER

Karl Racine, Houston, and Vernon P. Shelton,
San Antonio, Tex., assignors to National In-
strument Corporation, Houston, Tex., a corpo-
ration of Texas

Application January 3, 1946, Serial No. 125,254

Term of patent 14 years

(Cl. D61—1)

To all whom it may concern:

Be it known that we, Vernon P. Shelton, a citizen of the United States, residing at San Antonio, county of Bexar, State of Texas, and Karl Racine, a citizen of the United States, residing at Houston, county of Harris, State of Texas, have invented a new, original, and ornamental Design for a Photographic Enlarger, of which the following is a specification, reference being had to the accompanying drawing, forming a part thereof.

The figure is a perspective view of a photo-
graphic enlarger showing our new design, the op-
posite side presenting substantially the same ap-
pearance as the side shown, and the rectangular
base being broken away at the ends thereof for
convenience of illustration.

We claim:

The ornamental design for a photographic en-
larger, substantially as shown and described.
